Filed July 3, 1961, Ser. No. 121,465

9 Claims. (Cl. 338—97)

This application relates to a resistor for introducing resistance into an electrical circuit. The resistor is constructed so as to make unprecedented provision for the circulation therethrough of air to prevent overheating of the resistor. Also the resistor is made up of elements which when assembled provide for exceptionally good electrical conductivity therebetween. The resistor is of comparatively simple construction, economical to manufacture, compact and of light weight. I accomplish improved results while at the same time effecting a reduction in cost.

I provide a resistor comprising supporting means including spaced apart members of non-conducting material, such members having openings therein, an elongated resistance element having a body of coil form, the end portions of the resistance element entering the openings in the spaced apart members, and means mounting the resistance element to the supporting means, the supporting means being open transversely of the resistance element to permit air circulation transversely through the coil. The end portions of the resistance element and the means mounting the resistance element to the supporting means preferably have openings therethrough extending generally in the direction of the length of the resistance element to permit additional air circulation through such openings. The end portions of the resistance element may comprise externally threaded nipples having axial openings therethrough, and the means mounting the resistance element to the supporting means may comprise nuts threaded onto the externally threaded nipples.

I preferably provide a plurality of elongated resistance elements each having a body of coil form with the end portions of the resistance elements entering the openings in the spaced apart members of the supporting means together with electroconductive connectors connecting adjacent end portions of resistance elements and means mounting the resistance elements and the connectors to the supporting means.

I further provide a resistance element comprising a coil having applied to the ends thereof by weld means mounting means having externally threaded portions for mounting the resistance element in a supporting structure. The coil may have an internally threaded end member applied in generally coaxial relation to the coil by weld means and means including an externally threaded nipple may be threaded into the internally threaded end member for mounting the resistance element in a supporting structure.

More specifically my resistance element may comprise a coil having applied to an end thereof an end structure comprising means for mounting the resistance element in a supporting structure, the end structure having therethrough a tapered opening adapted to act as a socket to receive a plug in electroconductive relation thereto and when no plug is in the socket to permit circulation of air through the end structure. The end structure may comprise a central projection externally threaded to receive a nut to fasten the resistance element to a plate or connector through which the central projection is adapted to pass and at least one boss or protuberance beside the central projection adapted to enter a cavity in the plate or connector to establish an electrical connection between the resistance element and the plate. The pro-

2

tuberance and the cavity are preferably tapered to afford tight frictional engagement therebetween enhancing the electrical conductivity of the connection between the resistance element and the plate. I find it desirable to employ diametrically opposed protuberances on opposite sides of the projecting portion of the end structure of the resistor and correspondingly positioned cavities in the connector receiving the protuberances. However, the protuberances may be formed on the connector and the cavities may be formed in the end structure.

Other details, objects and advantages of the invention will become apparent as the following description of a present preferred embodiment thereof proceeds.

In the accompanying drawings I have shown a present preferred embodiment of the invention in which

FIGURE 1 is a plan view of one complete resistor and a portion of a second resistor showing means for electrically connecting the resistors together;

FIGURE 2 is a side view of the complete resistor shown in FIGURE 1;

FIGURE 3 is a cross-sectional view taken on the line III—III of FIGURE 2;

FIGURE 4 is an isometric view of a plate or connector with a portion cut away;

FIGURE 5 is an isometric view of the resistor end structure; and

FIGURE 6 is a cross-sectional isometric view of the resistor end structure to show the tapered socket therein.

Referring now more particularly to the drawings, my resistor comprises a case designated generally by the reference numeral 2 which may be of any suitable material, such as metal or plastic, with opposed ends 3 and four sides 4 provided with openings 5 for the circulation of air through the resistor. Mounted in the case 2 are spaced apart supporting means 6 of non-conducting material such as Transite, such members being shown as being positioned respectively adjacent the ends 3 of the case. Another member 7 of similar material is shown intermediate the members 6. The member 7 may be omitted if desired, particularly if the resistor is short in the direction between the ends 3; if the resistor is relatively long in the direction between the ends 3 the member 7 is preferably utilized to assist in insuring maintenance of proper positioning in the case of the resistance elements now to be described.

The resistor mounted in the case 2 comprises two resistance elements each designated generally by reference numeral 8. The resistance elements 8 may be constructed in generally similar manner so description of one will suffice for both. Each resistance element 8 has a body in the form of a coil 9 (although the coils are shown as being specifically different as to size of wire and pitch) and end structures designated generally by reference numeral 10 at its respective ends. Each coil 9 is wound from high resistance stainless steel wire which is corrosion resistant and laterally open (i.e., the convolutions of the coil are spaced apart) to permit cooling air entering the case through the openings 5 to pass between the convolutions of the coil to cool the coil. Such shape of the coil also sets up a turbulence of the cooling air which enhances the cooling effect.

Welded to each end of the coil 9 is an end structure 10 as shown in FIGURES 5 and 6. Each end structure 10 comprises an internally threaded end member 11 which is welded to the coil in generally coaxial relation thereto by weld metal 12. Threaded into each end member 11 is an externally threaded nipple 13 having a tapered opening 14 therethrough adapted to act as a socket to receive a tapered plug in electro-conductive relation thereto as will presently be described and when no plug is in the socket to permit circulation of air through the end structure. The nipple 13 is preferably

welded to the end member 11 by weld metal 15. The word "weld" is used herein as a word of broad definition and not of limitation and includes a connection formed by processes analogous to welding such as brazing, soldering, etc. By the same token the term "weld metal" comprehends brazing metal, soldering metal, etc. The end member 11 with the nipple 13 permanently attached thereto as above described jointly form the end structure 10 of the resistance element with the nipple constituting a projecting portion of the end structure. The end member 11 has diametrically opposed tapered bosses or protuberances 16 for a purpose to be presently described.

The resistance elements 8 are disposed in openings 17 in the supporting members 6 and in correspondingly positioned openings 18 in the intermediate member 7 if such an intermediate member is employed. A plate or connector 19 as shown in FIGURE 4 is applied to each end of the resistor. Each connector 19 has two openings 20 for receiving the projecting portions 13 of the end structures of the two resistance elements, tapered cavities 21 for receiving the protuberances 16 and a central hole 26 for receiving a self-tapping screw to fasten the connector to the adjacent supporting member 6. Each cavity 21 is tapered from relatively great transverse dimension toward the inside of the resistor to relatively small transverse dimension toward the outside of the resistor. Similarly each protuberance 16 is tapered from relatively great transverse dimension toward the inside of the resistor to relatively small transverse dimension toward the outside of the resistor providing for easy entry of the protuberances 16 into the cavities 21 and for insuring a tight frictional connection between each protuberance and the wall of the corresponding cavity and optimum surface contact between the resistance element and the connector whereby to enhance the electrical conductivity of the connection between the resistance element and the connector and hence also the electrical conductivity between adjacent resistance elements which are electrically connected by a connector. Nuts 23 are threaded onto the nipples 13 and tightened against the connectors 19 and serve the dual function of mounting the resistance elements in the case and tightly pressing the tapered protuberances 16 into the tapered cavities 21. When the nuts 23 are tightened the connectors 19 are pressed against the outer faces of the supporting members 6, the resiliency of the springs 9 insuring a firm and tight connection at both ends of the case.

A conductor 24 may be provided with tapered plugs 25 at its ends which may be introduced into the tapered sockets 14 of resistance elements in adjacent resistors so as to electrically connect the resistors together. The taper of the plugs 25 and the taper of the sockets 14 may be substantially the same so that the plugs are maintained in the sockets by frictional engagement over a large surface area. This insures retention of the plugs in the sockets and an optimum electrical connection between adjacent resistors.

The end members 11 and the connectors 19 are desirably cast out of high strength low resistance bronze which can be welded to stainless steel at about 1500° F. which is the annealing temperature of the wire used for the coils. The end members are welded to the coils by deposit welding employing a welding rod and in such manner as to maintain fusion of the weld metal at the annealing temperature of the coil wire. The supporting members 6 and 7 may be made of Transite treated to resist temperatures of 2300° F., heat load and shock and provide insulation for 10,000 volts between coils and ground.

While I have shown and described a present preferred embodiment of the invention it is to be distinctly understood that the invention is not limited thereto but may be otherwise variously embodied within the scope of the following claims.

I claim:

1. A resistor comprising supporting means including spaced apart members of non-conducting material, said members having openings therein, an elongated resistance element having a body of coil form, the end portions of the resistance element entering said openings, and means mounting the resistance element to the supporting means, the end portions of the resistance element and the means mounting the resistance element to the supporting means having openings extending completely therethrough generally in the direction of the length of the resistance element to permit air circulation therethrough.

15 2. A resistor comprising supporting means including spaced apart members of non-conducting material, said members having openings therein, an elongated resistance element having a body of coil form, the end portions of the resistance element entering said openings, and means mounting the resistance element to the supporting means, the supporting means being open transversely of the resistance element to permit air circulation transversely through the coil, the end portions of the resistance element and the means mounting the resistance element to the supporting means having openings extending completely therethrough generally in the direction of the 20 length of the resistance element to permit additional air circulation through the last mentioned openings.

25 3. A resistor comprising supporting means including spaced apart members of non-conducting material, said members having openings therein, an elongated resistance element having a body of coil form, the end portions of the resistance element entering said openings, and means mounting the resistance element to the supporting means, the end portions of the resistance element comprising externally threaded nipples having axial openings extending 30 completely therethrough and the means mounting the resistance element to the supporting means comprising nuts threaded onto the externally threaded nipples.

40 4. A resistance element comprising a coil having an internally threaded end member applied in generally coaxial relation to the coil, weld means for fastening said member to the coil and means including an externally threaded nipple threaded into the internally threaded end member for mounting the resistance element in a supporting structure.

45 5. A resistance element comprising a coil having applied to an end thereof an end structure comprising means for mounting the resistance element in a supporting structure, the end structure having a tapered opening extending completely therethrough adapted to act as a socket 50 to receive a plug in electroconductive relation thereto and when no plug is in the socket to permit circulation of air through the end structure.

55 6. A resistance element comprising a coil having applied to an end thereof an end structure comprising a central projection externally threaded to receive a nut to fasten the resistance element to a plate through which the central projection is adapted to pass and an outwardly projecting protuberance adapted to enter a cavity in the plate to assist in relatively positioning the end structure and the plate and enhancing the electrical connection between the resistance element and the plate.

60 7. A resistor comprising a resistance element having an end structure comprising a projecting portion, a plate having an opening through which the projecting portion 65 of the end structure of the resistance element extends, means cooperating with the part of the projecting portion of the end structure which extends through the opening in the plate and with the plate to fasten the resistance element and the plate together, one of the end structure and the plate having protuberance means and the other thereof having cavity means receiving the protuberance means to assist in relatively positioning the end structure and the plate and enhancing the electrical connection between the resistance element and the plate.

75 8. A resistor comprising a resistance element having

an end structure comprising a projecting portion, a plate having an opening through which the projecting portion of the end structure of the resistance element extends, means cooperating with the part of the projecting portion of the end structure which extends through the opening in the plate and with the plate to fasten the resistance element and the plate together, one of the end structure and the plate having tapered protuberance means and the other thereof having tapered cavity means receiving the protuberance means to assist in relatively positioning the end structure and the plate and enhancing the electrical connection between the resistance element and the plate.

9. A resistor comprising a resistance element having an end structure comprising a projecting portion, a plate having an opening through which the projecting portion of the end structure of the resistance element extends, means cooperating with the part of the projecting portion of the end structure which extends through the opening in the plate and with the plate to fasten the resistance

element and the plate together, one of the end structure and the plate having protuberance means and the other thereof having cavity means receiving the protuberance means to assist in relatively positioning the end structure and the plate and enhancing the electrical connection between the resistance element and the plate, the end structure having a tapered opening extending completely therethrough adapted to act as a socket to receive a plug in electroconductive relation thereto and when no plug is in the socket to permit circulation of air through the end structure.
